GRINDING MACHINE AND METHOD

Sol Einstein, Cincinnati, Ohio, assignor, by mesne assignments, to The Heald Machine Company, Worcester, Mass., a corporation of Massachusetts

Application October 26, 1931, Serial No. 571,028

3 Claims. (Cl. 51—103)

This invention relates to improvements in machine tools and especially to improvements in grinding machines for, and in a method of, grinding irregularly shaped work pieces.

5 An object of this invention is the provision of a grinding machine for the centerless grinding of the bore of hollow work pieces whose outer surface is not cylindrical or not concentric with the axis of the bore to be ground.

10 Another object of the invention is the provision of a grinding machine for grinding the bore or hole of irregularly shaped articles concentric with a predetermined axis.

15 A further object of the invention is the provision of an improved internal grinding machine adapted to grind or generate the hole or bore of work pieces normally difficult to handle together with improved means for supporting such work pieces and effecting their rotation.

20 Other objects and advantages of the present invention will be readily apparent by reference to the following specification taken in connection with the accompanying drawings and it will be understood that any modification may be made 25 in the specific structural details there illustrated within the scope of the appended claims without departing from or exceeding the spirit of the invention.

In the drawings:

20 Figure 1 is a front elevation of a grinding machine embodying this invention.

Figure 2 is a fragmentary view of certain parts of the machine in elevation as particularly seen from line 2—2 of Figure 1.

35 Figure 3 is a sectional view taken on line 3—3 of Figure 1.

Figure 4 is a sectional view taken on line 4—4 of Figure 2, illustrating in section one form of work holding means.

40 Figure 5 is an elevation of a modified work holding means.

Figure 6 is a sectional view taken on line 6—6 of Figure 5.

45 Figure 7 is an elevation of a further modification of a work holding means.

Figure 8 is a sectional view on line 8—8 of Figure 7.

Figure 9 is an enlarged elevation of one of the reversing dogs for the table.

50 Throughout the several views of the drawings similar reference characters are employed to denote the same or similar parts.

In the past work pieces of an irregular shape or contour have been mounted in suitable chucks mounted on rotating shafts or spindles in line

with a small diameter or internal grinding wheel. By reason of the inability to remount a work piece a second time in the chuck in the same position with the axis of the bore being ground precisely concentric to the axis of rotation of the 5 chuck, such irregular work pieces must be completely ground at one operation by a single grinding wheel which is generally a compromise between a roughing and finishing wheel and does not necessarily provide the desired finish. Recently 10 work pieces have been ground internally by the centerless method which consists in rotating the work on a previously ground external surface thereby grinding or generating a bore precisely concentric with the axis of the external 15 surface. This invention pertains primarily to the apparatus and method for grinding irregularly shaped objects by the same centerless machines as those in which cylindrical work pieces are now being ground. 20

The machine for accomplishing this purpose corresponds to the usual precision centerless grinding machine and comprises a bed 10 having formed on its upper surface ways 11 on which a wheel head 12 is movable. This head comprises 25 a slide 13 movable on the ways 11 and supporting a spindle housing 14 in which is journaled a wheel spindle 15. The slide 13 also carries a prime mover or motor 16 belted or otherwise connected with the spindle 15 through suitable mechanism 30 enclosed within a housing 17. The motor 16 is adapted to drive the spindle 15 at a high rate of speed for correspondingly rotating the small diameter or internal grinding wheel 18 secured thereto at a suitable speed for grinding. On a 35 lateral extension 19 of the bed there is mounted a base plate 21 supporting the cross-slide 23 on which the work piece 20 is mounted. A dovetailed guideway 22 on the base plate 21 provides for guiding said cross or transverse slide 23 which carries the work supporting and rotating mechanism. This work supporting and rotating mechanism comprises a spindle 24 journaled in a suitable housing 25 integral with or secured to the slide 23 and forming part of the workhead. A 40 worm wheel 26, Fig. 3, is secured to the spindle 24 intermediate its ends and the spindle 24 carries on its free end a friction drive or work regulating wheel 27. The spindle 24 is rotated through the worm wheel 26 by means of a worm 28 secured to 45 or integral with a shaft 29 vertically journaled in the housing 25 and passing through the slide 23 and base plate 21 to the interior of the bed 10. To the lower end of the shaft 29 is secured a bevel gear 30 meshing with a complementary beveled 50

55 gear 31 meshing with a complementary beveled gear 32.

5 gear 31 having a sleeve 32 which is suitably journaled in a bearing 33 integral with and depending from the guide bracket 34 of the housing 25. The sleeve 32 of the gear 31 has a sliding splined connection with a countershaft 35 journaled in a bracket 36 carried by the base plate 21. Secured to the shaft 35 is a cone pulley driven by a belt or the like from any suitable source.

Opposite to the regulating wheel 27 is a pressure roller 38 rotatably journaled in the upper end of an arm 39 secured at its other end to a shaft 40 extending lengthwise of the wheel head 20 and terminating in a pinion 41 enclosed within cylinder housing 42. Axially slideable through the cylinder 42 is a piston 43 having rack teeth 44 meshing with the pinion 41. The piston 43 is actuated by fluid under pressure from a suitable source and, through the rack and pinion connection, effects an oscillation of the shaft 40 about 10 its axis thereby shifting the pressure roller toward and from the regulating wheel 27 for the insertion and removal of work positioned between said wheel and roller.

20 The workhead is provided with a bracket 61 located intermediate the axis of the shaft 40 and spindle 24. Said bracket 61 carries a work support in the form of a blade 68 having an active supporting surface inclined in the direction of the operative face of the regulating wheel and forming 25 between said wheel and blade a work-receiving trough, into which a work piece is normally urged by the pressure roller.

30 The work piece illustrated in Figures 2 and 4 is a bevelled pinion having the bore 46 therein, on which the grinding operation is to be performed. As shown in Figure 4 the pinion 46 is mounted against a locating plate 47 which has projecting from it three lugs 48, Fig. 2, of a pitch equal to the pitch of the gear 45 and adapted to 35 enter the space between certain of the pinion teeth for properly centralizing the pinion relative to the plate 47. From this it will be seen that the work piece is centralized relative to the plate 47 in accordance with the pitch circle thereof. 40 The plate 47 is held by means of screws or the like 49 against cap member 50 which is in turn secured by means of screws 51 to a drum or thimble 52 having a cylindrical outer surface. The drum or thimble 52 has its axis absolutely co-55 axial with the axis of the cap 50 and locating plate 47. Consequently, the pinion 45, when centralized relative to the locating plate 47 as above described, has the center of the pitch circle coinciding precisely with the axis of the cylindrical outer surface of a thimble.

55 The thimble 52 is provided with a flange 53 depending from the interior wall thereof and forming a bearing for a clamp nut 54. The clamp nut 54 is held against axial movement relative to the thimble 52 by means of the flange 53 and a plate 55 fastened to the rear end of the thimble 52. Nut 54 has a threaded connection with the shank 56 of a clamping head 57 which terminates in flange or head 58 to which are pivoted, at equally spaced points, such as 59, arms 60 which extend 60 through openings 61 formed in the thimble cap 50 and locating plate 47. The arms 60 terminate 65 in hook fingers 62 adapted to engage with the face of the work. The arms 60 are further provided on their outer surfaces with cam faces 63 adapted to co-operate with cam surfaces 64 formed at the end of the openings 61 formed in the cap 50, above referred to. A spring pressed 70 plunger 65 carried by the head 58 tends to oscillate each arm 60 in a counter-clockwise direction about pivot 59 thereby maintaining contact between the upper surface of the arm 60 and the upper surface of the opening 61.

75 The operation of the work holding mechanism is as follows: The nut 54 is rotated by means of a suitable spanner wrench cooperating with sockets 66 formed in the clamp nut 54 for shifting the clamp head 57 to the right as seen in Figure 4. As soon as the arms 60 have been projected 10 through the openings 61 a distance to permit cam faces 63 and 64 to clear one another, the spring pressed plunger 65 actuates said arm outwardly thereby freeing the work piece from the clamping pressure. An unfinished work piece is then 15 substituted for the one previously finished whereupon the clamp nut 54 is actuated in the opposite direction for drawing the clamp head 57 to the left, as seen in Figure 4, carrying with it the arms 60 which through the interengagement of cam 20 faces 63 and 64 are actuated against the resistance of spring pressed plunger 65 for clamping the work against the locating plate 47, with the center of the pitch circle of the gear precisely 25 concentric to the axis of the cylindrical outer surface of the thimble.

With the work now clamped in position in the thimble 52 with the axis of the pitch circle of the gear co-axial with the axis of said thimble 52, the latter is positioned in the above described work-head for rotation on its cylindrical outer surface. The thimble, in grinding position, engages with the regulating wheel and the supporting blade 68 and the pressure roller 38 tends to force the thimble 52 against the surface of the regulating wheel 27 whereby rotation of the said regulating wheel effects rotation of the thimble 52 and all parts carried thereby about the axis of the said finished exterior surface of the thimble. It will be apparent that the rotation of the thimble by 40 this workhead procures a rotation of the work piece therein about an axis coinciding with the center of the pitch circle of the gear teeth on said work piece.

45 The grinding wheel carriage 12 is now actuated to the left as seen in Figure 1, to position the grinding wheel within the bore of the work piece, by any suitable or desirable means such as the mechanism disclosed in co-pending application of Einstein, Booth and Haas, Serial Number 374,556 filed June 28, 1929. This mechanism terminates in a pivoted lever 70 for reversely actuating a suitable hydraulic control valve of any well-known construction as, for example, the valve disclosed in Patent No. 1,582,468, granted April 27, 1926 to Heald and Guild. The lever 70 is secured to a pivot shaft 71 which has depending from it the arm 72. Dogs 73 and 74 co-operate with the upper end of the lever 70 for reversing the movement of the wheel head at each end of 60 its stroke, as is the usual practice with this type of grinding machine and as shown in the co-pending application above referred to, thus providing for a reciprocation of the grinding wheel over the surface of the work piece. After the grinding wheel has entered the bore of the work, the slide 23 is shifted transversely on the bed along guide-way 22 to relatively feed the work and wheel and effect the desired stock removal from the work. This is accomplished by the arm 72 which is pivoted as at 75 to one end of a link 76 which has its other end pivoted at 77 to an arm 78 keyed or otherwise secured to an oscillatable stub shaft 79. The shaft 79 is journaled in the walls of a box or casing 80 secured to the forward face of the 75

bed 10 and enclosing the intermittent feeding mechanism now to be described.

Secured to the shaft 79 inferiorly of the casing 80 is a wedge shaped cam 81 adapted to engage 5 the roller 82 rotatably carried by a bell crank lever 83 pivoted at 84. The lever 83 is actuated in one direction about its pivot 84 by means of a spring 85 having its opposite ends secured respectively to an anchor within the casing 80 and 10 the bell crank lever 83. The free end of arm 86 of lever 83 is furcated as at 87 and receives therein the pin 88 projecting from the rod 89 on bell crank 90. The bell crank 90 carries on its other arm a pawl 91 co-operating with a ratchet 92 of 15 any suitable cross feed mechanism for actuating the pinion 93, Fig. 3, on the end of a cross feed screw 94. The screw 94 is threaded into a nut 95 depending from the under surface of the slide 23.

It will be noted that the reversing dog 74 is pivotally mounted on a movable core 96 of solenoid 97 adjustably carried by the wheel head slide 13. The dogs 73 and 74 determine the normal reciprocatory stroke of the wheel head while the grinding wheel is within the work for breaking up 25 grinding lines on the work. This stroke does not permit the wheel head to carry the wheel outside of the work which is necessary in order to replace the finished work piece with an unfinished one. The dog 74 is therefore withdrawn from the path 30 of the lever 70 at the conclusion of the grinding operation, and is effected by energizing the solenoid 97 through electrical means. The means for this purpose may reasonably take the form of a suitable electrical circuit with a switch member 35 98, Fig. 3, in the circuit, the latter being closed by the gear 41 during retraction of the pressure roller 38 from contact with the thimble 52. This retraction of the reversing dog 74 permits an extended stroke of the wheel head which continues 40 until the third dog 99 on the slide 13 engages with and actuates the reversing lever 70, thereby reversing the hydraulic control valve, above mentioned, for returning the wheel head to its grinding position. The time limit during which the 45 extended stroke takes place is sufficient to permit the replacement of the thimble in the work-supporting structure by another thimble having an unfinished work piece positioned therein. It will be noted that the slide 13 may be brought 50 to rest when the grinding wheel is withdrawn from the bore of the work piece by manual operation of the lever 70.

The operation of the grinding machine is as follows: The work piece is first properly centralized and clamped within the thimble 52 whereupon it is placed on the work rest blade 68 and in engagement with the regulating wheel 27. The piston 43 is then actuated in the proper direction for oscillating the arm 39 and urging the pressure roller 38 into contact with the thimble 52 forcing the same into the work receiving trough formed by the inclined edge 69 of the blade 68 and the active face of the wheel 27. The wheel 27 being constantly rotated effects the rotation 55 of the thimble and work carried thereby. The lever 70, which has been in mid-position in which position the slide carrying the grinding wheel is supported against movement from the inoperative position of Fig. 1 in the usual manner, is then 60 manually actuated to effect movement of the slide 13 to the left which causes the grinding wheel 18 to enter the bore in the work. The wheel head 12 is automatically reciprocated in operative relation to the work at the end of its initial stroke 65 to the left into operative position and then oper-

ates the feeding mechanism as above described for effecting the relative cross feed between the work and grinding wheel to reduce said work to the desired size.

It will be noted that the work piece is rotated 5 about the axis of the pre-formed cylindrical outer surface of the thimble 52 which has the work properly centralized therein so that the axis of the hole or bore in the work is co-axial with the said pre-formed surface of the thimble. This insures absolute rotation of the work about the desired axis.

The thimble may be arranged for holding work pieces other than the gears or pinions shown in Figures 2 and 4. A modified showing is illustrated in Figures 5 and 6 in which the cap or cover plate 100 is provided with a depression or seat 101 conforming substantially with the contour of the work. In this construction a hook or clamp member 102 is provided which is carried 20 by the head 103 and actuated by the clamp nut 54 for holding the formed work 104 within the seat 101. In this construction the seat 101 is so formed as to have the axis of the hole or bore to be ground will be located coaxially with the axis 25 of the cylindrical outer surface of the thimble body 52.

Figures 7 and 8 show a further modification for clamping formed work pieces to the thimble 52. This modification again consists of a head 105 having an opening 106 formed therein substantially to the contour of the work piece to be operated upon. Inferiorly of the body portion of the thimble there is mounted a ring 107 supporting a plate 108 against which the work piece rests. 30 In this modification the head 109 has pivoted thereto a pair of clamp arms 110 for holding the work against the base plate 108. The head and plate 109 and 108 are provided with central apertures 111 and 112 co-axially aligned with the axis 40 of the outer surface of the thimble. The said apertures receive therein the reduced portion 113 of a centralizing and positioning pin 114 having an enlarged portion 115 adapted to enter the bore or hole in the work and thereby centralize the 45 work relative to the cylindrical outer surface of the thimble 52. In other words, the work piece has a bore or hole therein substantially equal to the enlarged portion 115 of the pin on which it is mounted and then the work piece and pin are 50 positioned in the thimble so that the reduced portion 113 of the pin passes through the apertures 111 and 112 in the clamp head and plate respectively whereupon the clamp nut 54 is actuated for causing the clamp finger 110 to secure the work 55 against the base plate 108. With this construction the work is centralized in the thimble 52 whereupon it may be mounted on the work rest blade with the assurance that the work will rotate about the axis of the bore which is co-axial with 60 the axis of the thimble.

If desired a similar centralizing and positioning mechanism may be employed with the modification shown in Figures 2 and 4, or in the modification of Figures 5 and 6.

What is claimed is:

1. In a centerless internal grinding machine, the combination with a grinding wheel, and means for supporting and rotating a cylindrical member on its cylindrical outer surface, said means and wheel having a relative transverse movement for a cross-feed between said wheel and said means, said supporting and rotating means including a regulating wheel having its axis substantially in the plane of the cross-feed

- movement, a work-support spaced from said regulating wheel, both said regulating wheel and support being engageable with the cylindrical outer surface of said member, and a pressure member also engageable with the cylindrical outer surface for holding said cylindrical member against the regulating wheel and work-support, of a thimble having a cylindrical outer surface and adapted to be removably positioned in 10 said supporting and rotating means with its cylindrical outer surface engaging with the regulating wheel, the work-support and the pressure member, and means within said thimble for clamping a work piece therein with the axis of the surface of 15 the work piece to be ground coincident with the axis of the cylindrical outer surface of the thimble, the latter providing for the rotation of the work piece by the supporting and rotating means during a grinding operation on said work piece, said 20 regulating wheel by its rotation procuring a rotation of the thimble.
2. In a centerless internal grinding machine, the combination with a grinding wheel and a centerless work-supporting structure, said wheel 25 and structure having a relative transverse movement for a cross-feed movement therebetween, said work-supporting structure comprising spaced work-supporting and rotating members engageable with the cylindrical outer surface of an annular member for supporting and rotating the same, the axis of rotation of one of said members being in substantial alinement with the plane 30 of the cross-feed movement for backing up the annular member, of a thimble having a cylindrical outer surface, and means within said thimble 35 for clamping a work piece therein with the axis

of the surface to be ground coincident with the axis of the cylindrical surface of the thimble, said thimble being removably positioned within the work-supporting structure with its cylindrical outer surface engaging with the supporting 5 and rotating members and being rotated by the rotation of one of said members.

3. A work-holding and rotating mechanism for non-cylindrical or formed work pieces for use in connection with internal grinding machines in 10 which there is provided a cross-feed movement between the grinding member and the work-supporting member, said mechanism comprising a centerless work-supporting structure including a rotating regulating wheel having its axis sub- 15 substantially in the plane of the cross-feed movement, a work-support spaced from said wheel and a pressure member spaced from said wheel and support, said wheel support and member each being engageable with the cylindrical outer surface of a member positioned therebetween, a thimble having an exteriorly finished surface of revolution and adapted to be positioned within said supporting structure with its finished surface engaging with said regulating wheel and 20 work-support and being held in engagement therewith by the pressure member whereby said thimble is supported and rotated on its exteriorly finished surface, said thimble being positively rotated by the rotation of the regulating wheel, 25 and means within said thimble for supporting and clamping a work piece in said thimble with the axis of the bore of the work piece coincident with the axis of the surface of revolution of the 30 thimble.
